United States Patent Office

Des. 197,721
Patented Mar. 17, 1964

197,721

DESK

Richard A. Wallace, Norristown, Pa., assignor to Bridge Incorporated, Philadelphia, Pa., a corporation of Pennsylvania

Filed Sept. 12, 1962, Ser. No. 71,659

Term of patent 14 years

(Cl. D33—7)

FIG. 1.

FIG. 2.

FIG. 3.

FIG. 7.

FIG. 4.

FIG. 6.

FIG. 5.

FIGURE 1 is a front perspective view of a desk showing my design wherein the extension member is shown in raised position.

FIGURE 2 is a side elevational view of the extension member as seen from the left of FIGURE 1, the dotted line portion having been omitted for convenience of illustration;

FIGURE 3 is an elevational view of the extension as seen from the left in FIGURE 2;

FIGURE 4 is a plan view of the extension member shown in its closed position;

FIGURE 5 is a side elevational view thereof;

FIGURE 6 is an elevational view of the extension as seen from the left in FIGURE 5;

FIGURE 7 is a fragmentary view of the extension of FIGURE 6 wherein the top member is partially elevated;

FIGURE 8 is a top plan view of the extension wherein the pivotal top member is in stored position;

FIGURE 9 is a side elevational view of the extension

as disclosed in FIGURE 8;

FIGURE 10 is an elevational view of the extension as seen from the left in FIGURE 9.

FIGURE 11 is an elevational view of the extension as seen from the left in FIGURE 10.

The dominant features of my design reside in those portions shown in full lines on the drawing.

I claim:

The ornamental design for a desk, substantially as shown and described.
